UNITED STATES PATENT OFFICE.

WILLIAM C. GREGG, OF HACKENSACK, NEW JERSEY, ASSIGNOR TO THE GREGG COMPANY, LIMITED, OF HACKENSACK, NEW JERSEY, A CORPORATION OF NEW YORK.

METAL UNDERFRAME FOR CAR CONSTRUCTION.

1,062,153.

Specification of Letters Patent.

Patented May 20, 1913.

Application filed May 10, 1912. Serial No. 696,419.

To all whom it may concern:

Be it known that I, WILLIAM C. GREGG, a citizen of the United States, residing at Hackensack, in the county of Bergen and 5 State of New Jersey, have invented certain new and useful Improvements in Metal Underframes for Car Construction; and I do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

My invention relates to under-frames for cars, particularly for cars of steel construction; and it has for its object to provide such an under-frame which will possess a high 20 degree of strength to resist stresses occurring in use and also be characterized by a degree of efficiency believed to be superior to constructions heretofore employed.

To the accomplishment of the foregoing 25 and such other objects as may hereinafter appear, the invention consists in features hereinafter particularly described and then sought to be clearly defined by the claims, reference being had to the accompanying 30 drawings forming a part hereof and in which:

Figure 1 is a plan view of a portion of an 35 under-frame embodying my invention; Fig. 2 is a section on the line 2—2 of Fig. 1 to which is added parts constituting a center pin and center bearing which may be employed in connection with the bolster construction of the under-frame; Fig. 3 is a section on the line 3—3 of Fig. 1; Fig. 4 is a section on the line 4—4 of Fig. 1; Fig. 5 is a section on the line 5—5 of Fig. 1; and Fig. 6 is a perspective of the center I-beam 40 and some of its attached parts.

In the specification and drawings reference will be made to the construction of one 45 end of the under-frame as that will be sufficient for an understanding of the construction of both ends of the under-frame as the features of invention will be the same at both ends of the under-frame, and a description 50 of one will be sufficient for both.

In the drawings, the numerals 1 and 2 55 represent, respectively, the side and end metal bars of the under-frame, between which will be employed suitable brace bars

or irons but as the same may be of any desired form and arrangement not constituting the present invention, an illustration of the same is not necessary.

The numeral 3 designates a center sill 60 consisting of an I-bar extending longitudinally and centrally of the frame and terminating relatively near the two ends of the under-frame adjacent to the bolster construction, and at such points being reduced 65 in depth by having a portion of the lower part of the I-bar cut away as illustrated in the drawings. To the opposite sides of the I-bar or beam are bolted angle bars 4 which lie above the lower edge of the I-beam and 70 extend through the bolster construction, terminating substantially at the edge of the top and bottom bolster plates, so as to carry the center sill construction practically 75 through the bolster construction. Extending through the bolster construction, from the inner edges of the top and bottom bolster plates, are two draft sills 5, formed preferably of channel bars, and running forward 80 to the end bars of the frame so as to form an open space for the application of the draft gear and the coupler (not shown) ordinarily employed in car constructions of 85 this general type. The bolster construction comprises transversely extending I-bar or beam members 6 which extend inwardly 90 from the side bars of the frame and terminate next to the draft sills 5 to which they are secured by angle plates 7 which are riveted to the bolster beams and to the draft 95 sills. The draft sills 5 are connected to the angle bars 4, which constitute an extension of the center sill, by means of spacing plates 8 which are U-shaped or channel-shaped in 100 cross-section and are riveted to the draft sills 5 and center sill angle bars 4, and also riveted to each other where they abut one against the other. Filling plates 9 are inserted between the web of the center sill and flanges of the spacing plates, and rivets 105 passed through flanges of the spacing plates and the filling plates as well as the web of the center sill. The top bolster plate 10 is riveted to the flanges of the bolster beam and to the flanges of the center sill as well as to the flanges of the draft sills; and the bottom bolster plate 11 is riveted to the bottom flanges of the bolster beam as well as to the bottom flanges of the draft sills and to 110 the flanges of the angle bars 4.

With the bolster and the center sill formed as described, and their parts together with the draft sills connected together as specified, the individual parts are tied to one another in a stable and compact form so that the maximum strength is obtained to resist stresses that may occur in the use of a car having its frame constructed as described. It is also to be observed that the individual parts composing the under-frame are made from structural iron or steel members so that the several parts may be readily fitted one to the other without requiring the parts to be specially formed for the purpose, the only alteration in the structural iron being in the cutting away of a portion of the center sill so as to permit the assemblage of the various parts as described, and thus the under-frame can be expeditiously made and its several parts so arranged in relation one to another and connected together as to form an under-frame of the most substantial construction and efficiency.

In connection with the under-frame constructed as described I may use a center bearing and a center pin comprising a body center plate 12, riveted to the bottom bolster plate, and having its lower end fitting within the truck center bearing 13, there being employed in connection therewith a king-pin 14 which will be secured to the body center plate by a key 15 passing through the body center plate and the king-pin as illustrated, and which may be held in place by a cotter pin passed through its end. It will be observed by constructing and applying the body center plate with the king-pin as described, the same are brought directly under the bolster construction and are attached to the bottom bolster plate, so that a very strong and simple and efficient construction is thus obtained.

I have illustrated and described with particularity the preferred special details of

construction but it is obvious that variations 45 may be made in some of the details and yet essential features of the invention retained so as to be embraced within the scope of the invention as defined by the appended claims.

Having described my invention and set 50 forth its merits what I claim is:—

1. A metal under-frame for car construction, comprising an I-beam center-sill, a bolster, L-shaped bars attached to the sides of the center-sill and entering the bolster, draft-sills parallel with and extending beyond the center-sill and its attached bars, and spacing members connecting the draft-sills with the center-sill and its attached bars. 60

2. A metal under-frame for car construction, comprising an I-beam center-sill having its lower portion at the ends cut-away to reduce its depth, a bolster, L-shaped bars attached to the sides of the I-beam to continue the I-beam construction within the bolster, bottom and top bolster plates, and means connecting the top flanges of the I center-sill and the bottom flanges of the L-bars to the bolster plates. 70

3. A metal under-frame for car construction, comprising an I-beam center-sill, a bolster, L-shaped bars attached to the sides of the center sill and entering the bolster, draft-sills parallel with and extending beyond the center-sill and its attached bars, spacing members connecting the draft-sills with the center-sill and its attached bars, top and bottom bolster-plates, and means connecting said plates to the draft-sills and 80 to the top flanges of the center-sill and bottom flanges of the L-shaped bars. 75

In testimony whereof I affix my signature in presence of two witnesses.

WILLIAM C. GREGG.
